UNITED STATES PATENT OFFICE

WILBUR A. COCHRANE, OF SEA CLIFF, NEW YORK

ACETYLENE LAMP

Application filed September 5, 1925. Serial No. 54,591.

This invention relates to improvements in acetylene lamps.

The object of the invention is to provide a construction which, while advantageous in a small lamp, is particularly efficient in a large lamp capable of containing a relatively large charge of carbide and water, and running for a considerable time.

With these general objects in view and some others which will appear from the description hereinafter, the invention consists in the features, details of construction and combinations of elements which will be fully described and more particularly pointed out in the following description and claims.

In the drawings:—

Fig. 1 is a vertical section partly in elevation;

Figs. 2 and 3 are horizontal sections on the lines 2—2 and 3—3, respectively, of Fig. 1, and

Fig. 4 is a detail section.

Referring to the drawings, A is a casing capable of holding water, this casing having a lower portion a , which is substantially cylindrical, and an outwardly extended upper portion a' , the purposes of which will be fully explained hereinafter. In order to increase the stability of the lamp, it is advantageous to provide the bottom of the casing with an outward extending base flange, as indicated at a^2 .

Within the casing there is placed a removable carbide receptacle B which is of a diameter nearly, but not quite, equal to the interior diameter of the lower portion a of the casing A, so that an annular space for water will be left between the receptacle and the said lower portion a . On the inside of the receptacle, and secured water tight to the bottom thereof, are arranged two tubes, one within the other, the one of larger diameter being indicated at C and the one of smaller diameter at D. These tubes may be secured to the bottom of the receptacle B in any suitable way. In

the preferred embodiment of the invention, the bottom of the receptacle is provided with a circular opening through which projects a bushing E' having a flange e soldered to the bottom. Into this bushing is screwed a plug 50 E, this plug being provided with a flange 1, arranged to seat against a packing washer 2 of suitable elastic material, for example, rubber. The inner end of the plug E has an annulus 3 outside of which fits tightly the tube 55 C. The tube D is arranged to fit tightly into the said annulus 3. The plug E is provided with a central opening as large as the bore of the inner tube D and in register with it.

A restricting rod, F, extends through the 60 opening in the plug E and through the bore of the inner tube D, this rod extending upward some distance above the top end of said tube D. The top end of the rod is screw threaded into a central hole in a plug G, to 65 which is secured a movable tube H, whose lower end telescopes into the annular space between the tubes C and D.

The lower end of the restricting rod F is advantageously provided with means by 70 which it may be rotated or reciprocated, as for example, by cranking the end of the rod as indicated at f, Fig. 1. This lower end of the rod F projects below the bottom of the receptacle B and in the best embodiment of 75 the invention may be so long that when the latter is placed in the casing A the lower end of the rod F will strike the bottom of the casing and thereby will be pushed upward relative to the receptacle B, thus lifting the 80 tube H.

Furthermore, means may be provided on the inner bottom face of the casing A for holding the restricting rod F against rotation relative to the casing, for a purpose hereinafter explained. This means may comprise a notch or recess whose side walls a^3 are formed by stamping the bottom inward, as shown in Fig. 1, the slope a^4 at each side be- 90

ing advantageous for the reasons hereinafter explained.

The movable tube H is longer than the tubes C and D and, when down, it rests on the plug E. The tube H is provided near its lower end with a plurality of holes as indicated at h for a purpose hereinafter explained. It extends some distance above the upper ends of the tubes C and D. When the tube H is 10 lifted by the rod F, the bottom of tube H will be lifted from contact with the plug E.

Outside the tube C is arranged a tubular member, I, which is vertically movable relative to the tube C and is spaced away from 15 said tube C a slight distance, for a purpose hereinafter explained. The tubular member is intended to be embedded in the calcium carbide, which is charged into the lower part of the casing, as indicated at K, Fig. 1. This 20 tubular member I is arranged to be lifted by the carbide as the latter swells under the action of the water which is fed to it. In practice, the friction between the carbide and the exterior surface of the tube I may be 25 sufficient to cause this lifting action. However, a more reliable action of this kind is obtained by making the tubular member I as a closed coiled wire helix, as indicated in the drawing, and a still further reliability 30 in lifting action is obtained by connecting the tubular member I to a cover device L arranged to rest on top of the carbide and to be lifted by the carbide as the latter swells. In practice, this cover device is in the form 35 of an annulus, which, however, is advantageously made sufficiently smaller in diameter than the interior diameter of the receptacle B, so as to permit the introduction of carbide into the bottom of the receptacle B 40 after the annulus L and the tubular member I are put in place.

A detachable cover M is provided for the receptacle B, this cover being so formed as to provide a downward-projecting skirt M', 45 an annular groove, and a central gas-dome m. Transversely of the dome-chamber there is fixed a cross-bar m' provided with at least two downward-extending posts, m², each having a lug, m³, these lugs projecting at right 50 angles from their respective posts, one lug in one direction, and the other lug in the opposite direction.

A filter-holding plate P is detachably held by the posts m². The plate has a diameter greater than the distance apart of the posts and has holes through which the posts and their lugs may pass. By rotating the plate the lugs are brought onto the plate and hold it 60 against displacement downward. This is a form of bayonet-joint serving to lock the plate in place and yet allow its removal by a backward rotation of the plate. For convenience of rotation, the plate is provided 65 with two downward-extending ears, p, which

may be stamped out of the plate metal and bent downward.

The plate P serves to clamp in place a filter Q of elastic material, such as felt, which is of larger diameter than the gas chamber and, therefore, is pressed tightly against the cover M by the plate P, as well as against the cross-piece m', so that it forms a lower wall for the gas-chamber in the dome m. To hold the cover M tightly against the top edge of its 70 receptacle B and maintain a gas tight joint at the packing ring N, while also allowing the cover to be readily detached, a special locking means is provided.

In the present example, this locking means comprises a plurality of resilient clamps each consisting of a helical spring, indicated at R, carrying a hook S at one end, arranged to hook over a lip m⁴ on the outside of the cover M, the other end of the spring carrying a catch-member T comprising a portion extending substantially parallel to the wall of the receptacle, and a portion arranged to project radially inward in contact with the bottom of the receptacle B which has its 80 bottom edge extended downward to enter the curve of the ring t, as shown in Fig. 1. In the preferred embodiment this inward projecting portion is made in the form of a loop or ring, as indicated at t, this loop serving as a finger hold to stretch the spring R when pulling the catch-member into place. In the best embodiment of the invention the rings 85 serve as feet for the receptacle, to support the latter in the casing.

In practice three of the resilient clamps are employed, these being arranged about 120° apart around the receptacle, thus properly distributing the stress on the packing ring N to insure a gas tight joint at all parts of said 90 packing ring, and, when serving as feet, to support the receptacle properly.

To the central part of the cover M at the gas-dome m is secured an upward-extending gas pipe or burner-tube U which supports a 100 gallery ring V (if such be desired to hold a globe), a pillar W and a burner tip w.

Also, the burner-tube U carries, at an intermediate part of its length, a cover Y for the casing A. This cover Y may be rigidly secured to the tube U as, for example, by soldering. A sleeve Z may surround the burner-tube between the casing cover Y and the gallery ring V, if desired the sleeve and gallery ring being held tightly in place by screwing the pillar W onto the end of the burner-tube U and tightly against the gallery ring. In the best embodiment of the invention, the casing cover Y is made as a dome and its lower edge is rimmed to fit telescopically outside an upward extending rim on the casing A.

The weight of the receptacle B with its contents, including the carbide, may be supported from the cover Y which rests on the 110

casing A, and the parts which carry this load are made strong enough for this purpose, the rings, *t*, in this case not quite touching the bottom of the casing. Where, however, the rings, *t*, serve as feet to support the receptacle and its attached parts, the casing cover Y is so located and arranged as to not quite rest on the casing A.

The operation of this lamp is as follows: 10 The casing cover Y and its attached parts are lifted from the casing, thereby leaving the casing empty. Water is then poured into the casing to such a height that when the casing cover Y and its attached parts are replaced, the water will rise about to the top of the casing.

The receptacle B is detached from its cover M by releasing the resilient clamps. This is done by pulling each of the catch-members 20 T downward and outward from the bottom of the receptacle and when they are free, lifting their hooks S from the lips *m*⁴.

The receptacle B is then filled about half way of its height with calcium carbide, which 25 may be done by removing the tubular member, I, filling in the required amount of carbide, and then forcing the tubular member I back into place, or, most advantageously, by pouring the carbide into the annular space 30 between the cover device L and the inner wall of the receptacle B, shaking the receptacle from time to time, if necessary, to shake the carbide down into place. Also it may be necessary to lift the cover device L and its 35 attached tubular member I to some extent to get enough carbide into the receptacle. After the receptacle has been charged with carbide, the receptacle cover M is replaced and locked to the receptacle B by replacing the clamps.

40 Then the receptacle is lowered into the water in the casing A, by the act of putting the casing cover Y onto the casing A, the water level rising in the casing. The contact of the rod F lifts the tube H from its contact with the 45 plug E and by proper manipulation, the cranked end *f* of the rod is caused to enter the slot or notch formed between the walls *a*³. The sloping portions *a*⁴ allow the cranked end *f* of the rod to ride up into place.

50 Owing to the substantially cylindrical shape of the lower part *a* of the casing and the fact that the receptacle nearly fills this part *a*, most of the water is driven up to the enlarged part *a'* of the casing, and because 55 this has a considerable diameter as compared with the lower part of the casing, the water level will fall very slowly as water is used by the carbide, thus causing but little change of 60 pressure on the supply of water to the carbide. In practice the parts are so dimensioned that all the carbide in the receptacle B will be used by the time the water level has fallen approximately to the plane of the 65 top of the cylindrical lower portion *a* of the

casing, whereupon the lamp is ready for recharging.

The water which fills the space in the casing around the receptacle, flows up through the hole in the bottom of the plug E around the rod F, thence upward through the annular space between the rod F and the inner wall of the tube D, overflows the tube D at its upper end and falls down the annular space between the outside of tube D and the inside of tube H. Thence the water flows outward under the lower end of the tube H and then upward in the space between the outside of tube H and then inside of tube C. It overflows the top of the tube C and falls downward in the space between the outside of tube C and the inside of the tubular member I. It escapes at the bottom of the latter member and wets the carbide at the lower part of the receptacle. This causes a generation of acetylene gas. The gas rises, passes into the upper part of the receptacle, which serves as a gas chamber, then passes through the filter Q, (which holds back any dust which may be in the gas) and enters the gas chamber in the gas-dome *m*. From there it passes to the burner. If at any time sediment clogs the lower end of the tube H, the water can escape through the openings *h*.

As the calcium carbide is acted upon by the water, it is converted into acetylene gas and calcium hydroxide. The latter occupies greater volume than the carbide so there is a gradual swelling of the solid contents of the receptacle, thus lifting the carbide which is above that strata already acted upon. This so-called "swelling of the carbide" causes the tubular device I to be lifted, on account of the friction between its outer surface and the surrounding carbide, as well as on account of the lifting of the cover device L which rests upon the upper surface of the carbide. Hence, during the running of the lamp, the tubular device I gradually rises, so that the water flowing to the carbide from the lowest end of I is distributed at different levels and hence is not compelled to flow through the carbide sludge to any great extent vertically. As the carbide sludge is more compact than carbide, it offers greater resistance to the flow, and there would be a slowing up in the generation of gas were it not for the gradual rising of the tubular device I.

If any obstruction occurs in these spaces which cannot be dislodged by the movement of the bell-tube, so that the light begins to lower, it is possible, without lifting out the receptacle, to cause a relative rotation of the rod F by merely rotating the lid Y, which causes a rotation of the carbide receptacle B, while the crank arm *f* is held stationary by the casing bottom. In extreme cases the receptacle may be lifted out and the rod F reciprocated or rotated by hand, thus dis-

lodging any foreign matter in the water which may be lodged in the tubes so that the water may get through more rapidly.

It will be noted that by the series of tubes, arranged as shown and described, a long restricted water channel is obtained in a relatively short height, and because of this length, even when the cross-sectional area of the water channel is of fair size, the restriction is sufficient to cause a relatively slow feed of the water sufficient to sustain the proper generation of gas for a considerable interval of time. In this way it is possible to make a table lamp with relatively large storage capacity for carbide and water, yet to generate the gas only at the rate needed for a good burner while at the same time avoiding any such very small, easily obstructed water-ducts as have heretofore been considered necessary in such lamps. Also, on account of this relatively long and tortuous water passage through the tubes, sudden fluctuations in gas pressure will not be so likely to blow back the water and break the water seal so as to allow the gas to escape. In this way, less fluctuation in gas pressure occurs than in those lamps where the water feed is readily fluctuated or set in oscillation by sudden variations in gas generation and then, by supplying an excess of water, due to such oscillations, causes an excess generation of gas at intervals.

The skirt M¹ of the cover M of the carbide receptacle serves to form a long water seal, so that if at any time the packing N should tend to allow gas to escape from the carbide receptacle, the water seal would serve to prevent such escaping gas from blowing out to the top of the water in the casing.

40 In practice it has been found that the gas pressure is maintained more nearly uniform than with prior devices, and this without the necessity of hand stirring to break up the sludge.

45 What is claimed is:

1. In an acetylene lamp, the combination, with a casing arranged to hold water, and a carbide receptacle arranged as a pressure chamber within the casing and spaced therefrom to provide a water space, said receptacle having a water passage in its bottom, of a plurality of concentric tubes spaced from each other, the walls of said tubes being spaced relatively close to one another so as to form a narrow passageway therebetween allowing a relatively thin sheet of water to flow in each such space, two of said tubes being fixed water tight to the bottom of the carbide receptacle, the inner of the said two tubes surrounding the opening at the bottom of the carbide receptacle, a movable tube located between and spaced from said two fixed tubes, the upper end of said movable tube being closed above the top end of the said inner tube, and a restricting rod secured to the up-

per end of said movable tube, extending through the said inner tube and projecting through the opening in the bottom of the water receptacle.

2. In an acetylene lamp, the combination, 70 with a casing arranged to hold water, and a carbide receptacle arranged as a pressure chamber and adapted to be rotated within the casing and spaced therefrom to provide a water space, said receptacle having a water passage in its bottom, of a plurality of concentric tubes spaced from each other, the walls of said tubes being spaced relatively close to one another so as to form a narrow passageway therebetween allowing a relatively thin sheet of water to flow in each such space, two of said tubes being fixed water tight to the bottom of the carbide receptacle, the inner of the said two tubes surrounding the opening at the bottom of the carbide receptacle, a movable tube located between and spaced from said two fixed tubes, the upper end of said movable tube being closed above the top end of the said inner tube, a restricting rod secured to the upper end of said movable tube, extending through the said inner tube and projecting through the opening in the bottom of the water receptacle, and means carried by the water casing for holding said restricting rod against rotation when the carbide receptacle is rotated.

3. In an acetylene lamp, the combination, 100 with a casing arranged to hold water, and a carbide receptacle arranged as a pressure chamber and adapted to be rotated within the casing and spaced therefrom to provide a water space, said receptacle having a water passage in its bottom, of a plurality of concentric tubes spaced from each other, the walls of said tubes being spaced relatively close to one another so as to form a narrow passageway therebetween allowing a relatively thin sheet of water to flow in each such space, two of said tubes being fixed water tight to the bottom of the carbide receptacle, 105 the inner of the said two tubes surrounding the opening at the bottom of the carbide receptacle, a movable tube located between and spaced from said two fixed tubes, the upper end of said movable tube being closed above the top end of the said inner tube, a restricting rod secured to the upper end of said movable tube, extending through the said inner tube and projecting through the opening in the bottom of the water receptacle, means carried by the water casing for holding said restricting rod against rotation when the carbide receptacle is rotated, and a tubular device arranged to be lifted by the swelling 110 of the carbide in the carbide receptacle, said tubular device surrounding the fixed tubes and being spaced away from the outer fixed tube to form a water passage.

4. In an acetylene lamp, the combination, 130 with a casing arranged to hold water, and

5 a carbide receptacle arranged as a pressure chamber within the casing and spaced therefrom to provide a water-space, said receptacle having a hole in its bottom, an outer fixed tube and an inner fixed tube within the receptacle, a plug arranged to close the hole in the bottom of the carbide receptacle, said plug being arranged to hold the lower ends of the outer and inner fixed tubes, a movable tube closed at its upper end above the inner tube and arranged to move in the space between the outer and inner fixed tubes, said movable tube being spaced from said outer and inner tubes to form water passages, said tubes being arranged close to one another so as to form a narrow passage therebetween allowing a relatively thin sheet of water to flow in said passages, and a restricting rod extending through the opening in the plug 10 and through the inner tube, said rod being secured to the top of the movable tube and having its lower end projecting below the carbide receptacle and into contact with the casing.

15 5. In an acetylene lamp, the combination, with a casing arranged to hold water, and a carbide receptacle arranged as a pressure chamber within the casing and spaced therefrom to provide a water-space, said receptacle having a hole in its bottom, of a plug arranged to close the hole in the bottom of the carbide receptacle, said plug having a circular passage for the admission of water and having an upward-extending annular flange, an outer fixed tube fitting tightly on the outside of said annulus, an inner fixed tube fitting tightly inside said annulus, a movable tube closed at its upper end above the inner tube and arranged to move in the space between the outer and inner fixed tubes, said movable tube being spaced from said outer and inner tubes to form water passages, said tubes being arranged close to one another so as to form a narrow passage therebetween allowing a relatively thin sheet of water to flow in said passages, and a restricting rod extending through the opening in the plug and through the inner tube, said rod being secured to the top of the movable tube 20 and having its lower end projecting below the carbide receptacle and into contact with the casing.

25 6. In an acetylene lamp, the combination, with a casing arranged to hold water, and a carbide receptacle arranged as a pressure chamber within the casing and spaced therefrom to provide a water space, said receptacle having a hole in its bottom, of an internally threaded collar fixed to said bottom 30 and projecting through the hole, a plug threaded into said collar and provided with a hole for the admission of water, and with a flange extending over the collar, a packing ring clamped between said flange and the collar, said plug having a circular pas-

35 sage for the admission of water and having an upward-extending annular flange, an outer fixed tube fitting tightly on the outside of said annulus, an inner fixed tube fitting tightly inside said annulus, a movable tube closed at its upper end above the inner tube and arranged to move in the space between the outer and inner fixed tubes, said movable tube being spaced from said outer and inner tubes to form water passages, said tubes being 40 arranged close to one another so as to form a narrow passage therebetween allowing a relatively thin sheet of water to flow in said passages, and a restricting rod extending through the opening in the plug, and through the inner tube, said rod being secured to the top of the movable tube and having its lower end projecting below the carbide receptacle and into contact with the casing.

45 7. In an acetylene lamp, the combination, with a casing arranged to hold water, a carbide receptacle located within the casing and spaced therefrom, the bottom of the receptacle being provided with a downward-projecting ridge, and a lid for said receptacle, said lid having a packing to engage the receptacle and having a retainer on its upper surface, of a locking device comprising a helical spring arranged to hook over the retainer on the lid, and a ring device arranged to fit over the ridge on the bottom of the carbide receptacle, the length of the locking device being such that when in place the spring will exert sufficient tension to hold the lid firmly to the receptacle.

50 8. In an acetylene lamp, the combination, with a casing arranged to hold water, a carbide receptacle located within the casing and spaced therefrom, the bottom of the receptacle being provided with a downward-projecting ridge, and a lid for said receptacle, said lid having a packing to engage the receptacle and having retainers on its upper surface, of a plurality of locking devices each comprising a helical spring arranged to hook over the respective retainer on the lid, and a ring device arranged to fit over the ridge on the bottom of the carbide receptacle, the length of each locking device being such that when in place the spring will exert sufficient tension to hold the lid firmly to the receptacle, said rings being arranged to rest on the inner surface of the bottom of the casing and serve as feet to support the carbide receptacle within the casing.

55 9. In an acetylene lamp, the combination, with a casing arranged to contain water, said casing having a substantially cylindrical lower portion, an upper portion of greater diameter than said lower portion and an upward extending rim, of a cylindrical carbide receptacle within the casing and less in diameter than the cylindrical portion of the casing, said receptacle being arranged to enter and nearly fill said cylindrical portion, means

for admitting water from the casing to the interior of the carbide receptacle, a lid detachably secured on said receptacle, a gas pipe secured to and extending upward from said receptacle lid and provided with a burner, a casing cover carried by said gas pipe and provided with a downward-extending rim arranged to telescope over the upward-extending rim of the casing, and means for supporting the carbide receptacle on the bottom of the casing at a distance therefrom to form a water space.

In testimony whereof, I have hereunto set my hand.
